UNITED STATES PATENT OFFICE

EARL E. BERRY, OF BELOIT, WISCONSIN, ASSIGNOR TO BELOIT IRON WORKS, OF BELOIT, WISCONSIN, A CORPORATION OF WISCONSIN

SCREEN TYPE FLOW EVENER

Application filed May 2, 1932. Serial No. 608,925.

This invention relates to paper making machines and more particularly to means for screening and evening the flow of the stock just prior to the application thereof to the web forming element.

It has heretofore been deemed necessary to first pass the stock through screens to disperse the fibers, separate out the slivers and uncooked wood, and produce uniformity in the stock, and then pass it into a head box for distribution to the wire or web forming element of the machine.

The stock coming from the screens is in the finest condition for making a good quality of paper because the fibers have just been dispersed and are uniformly distributed. It is, however, necessary to convert the flow of the stock from the screens to a smooth, flat stream that will flow out evenly without cross-currents or variations in velocity, to the full width desired on the web forming element. This presents many difficulties especially in view of the varying conditions arising during the operation of the machine, such as the variation in quality and consistency of the stock, and the differences in speed of the machine when operated for the production of various types of paper. Heretofore this has been accomplished by passing the stock into a head box or vat designed to even out the flow of the stock and conduct it onto the web forming element in the desired condition. However, the head box is not entirely effective to completely control the velocity and direction of flow of the stock and consequently the flow characteristics of the stock are not completely satisfactory in spite of the elaborate means provided. Furthermore, during the movement of the stock through the pipes connecting the screens and head box and through the head box itself, the condition of the stock—which may have been perfect upon leaving the screens—becomes impaired through accumulation of the fibers by settling in dead spaces, etc., thus producing bumpy or lumpy stock. Likewise, while the flow characteristics of the stock on leaving the screens approaches those re-

quired for transfer of the stock to the wire, they are completely disturbed through its delivery to the head box, whereby most of the work done by the head box is directed to overcoming objectionable velocity and directional flow characteristics induced by the transfer of the stock from screens to head box.

In my copending application Serial No. 458,922, filed June 2, 1930, entitled "Method and means for delivering stock for web forming", I have shown and described means adapted to replace the usual head box, wherein a rotating cylinder cooperates with other means for evening the flow of stock to the wire. The invention of the present application aims to combine the functions of the screens, the flow evener, and the head box and thereby completely eliminate the head box as a unit of the machine.

A further object is the provision of a device of such structure that the stock emerging therefrom is in a condition to be passed directly to the web forming element.

I have also aimed to provide a combined screen and head box of improved efficiency.

A further object is the provision of a structure of the character described wherein the mechanism and chamber may be raised and lowered with respect to the web forming element of the machine.

Another object is the provision of improved means for producing pulsation of the stock whereby dead areas and quiescent zones are eliminated and improved screening efficiency is obtained.

A further object is the provision of a structure having screening means and flow evening means arranged in a single chamber for screening the stock and substantially simultaneously evening the flow thereof.

I have also aimed to provide a device having means for evening out the flow of stock simultaneously with its passage through the screen and for conducting it directly onto the web forming element.

Other objects and attendant advantages will become apparent from the following de-

scription and the accompanying drawings in which—

Figure 1 is an end view of a machine embodying my invention;

5 Fig. 2 is a top view;

Fig. 3 is a section substantially on the line 3—3 of Fig. 2;

Fig. 4 is a section on the line 4—4 of Figure 1, and

10 Fig. 5 is a section on the line 5—5 of Fig. 4.

In a general way, the device consists of a chamber having an open side adapted to deliver stock directly to the web forming element of a paper making machine through conventional slices. An arcuate pulsating element is supported within the chamber on eccentrics and guides which impart, upon rotation thereof, an oscillatory motion to the pulsating element. A screening cylinder surrounds and is concentric with the pulsating element and means are provided for rotating the cylinder. Means are provided for feeding stock to the interior of the pulsating element through which it flows into the space adjacent to the screening cylinder where it is given desired flow characteristics by the screening cylinder so that it is suitably prepared for direct application to the web forming element. For every speed of the paper machine there is a certain desired head back of the slices. Means are provided whereby, without changing this head, the chamber may be adjusted vertically to bring about the desired immersion of the pulsating element and the screening cylinder.

Referring now more particularly to Figures 1, 3 and 4, the chamber consists of an arcuate bottom portion 7 secured at opposite ends to side walls 8 and 9. Troughs 11 and 12 are secured to the end portions 8 and 9 through flanges 13 and bolts 14, the troughs having an open side communicating with the interior of the chamber. The chamber is supported upon spaced standards 15, 16, 17 and 18, the end portions 8 and 9 being secured to these standards by means of bolts 19 which pass through flanged portions 21 and 22 of the ends and the standards, respectively, as best shown in Figure 1. Suitable slots 23 are provided in the flanges 21 and 22 to permit the chamber to be secured in any of a plurality of elevations. A fixed portion 24 of the chamber is positioned along an open side of the vertically adjustable portion just described and consists of an apron board 25 and vertical pond sides 26 and 27. Slices 28 and 29 of conventional design are supported between the pond sides 26 and 27 and serve to regulate the flow of stock to the web forming element 31 supported on the breast roll 32. An apron 33 also of conventional design is secured to the apron board 25 of the fixed portion 24. Deckle pulleys 34 and 35 may be supported upon the sides 26 and 27 if desired to support the

usual deckle strap 36. The portion 24 is fixedly supported upon the standards 16 and 18 and is secured to the end portions 8 and 9 of the chamber, through the bolts 19. Channel iron members 37, 38 and 39 extend between the end portions 8 and 9 and are secured thereto by brackets such as shown at 41. The channel iron members serve to reinforce the structure and to provide for supporting and for raising and lowering the same. The member 38 further serves to support the arcuate bottom 7 of the chamber as best shown in Fig. 3.

Means are provided for raising and lowering the movable portion of the chamber with respect to the fixed portion 24 and the standard. This may advantageously consist of gear boxes 42 and 43 positioned beneath the chamber and driven by a motor 44 or other prime mover. Screws 45 and 46 are positioned in the gear boxes 42 and 43 and are provided at their upper ends with feet 47 and 48 bearing against the lower side of the channel iron members 37 and 39. Upon operation of the motor 44 the gears of the gear boxes 42 and 43 will cause the screws 45 and 46 to be projected or retracted, thereby raising or lowering the movable portion of the chamber with respect to the fixed portion 24. The bolts 19 must, of course, be loosened to permit this operation and may then be again tightened to provide a liquid tight chamber.

In order to provide a continuous bottom for the chamber connecting the bottom 7 of the movable portion with the apron board 25 of the fixed portion a flexible, extensible connection is provided therebetween. This consists of parallelly spaced plates 49 and 51 flexibly connected to the bottom 7 by means of a piece of rubber 52 or other suitable flexible material, the plates 49 and 51 forming the groove of a tongue and groove connection. The tongue of this connection is formed by a plate 53 flexibly connected to the apron board 25 of the fixed portion by means of a flexible member 54 similar to that shown at 52, the plate 53 resting between the plates 49 and 51. This construction permits the plate 53 to move in and out of the space between the plates 49 and 51 depending upon the movement of the movable portion of the chamber to extend or contract the connection between these portions. The flexible portions 52 and 54 permit of the necessary change in angularity of the plates 49, 51 and 53 incident to the movement of the movable portion of the chamber. Two rows of spaced cams 55 and 56 are cast on the plate 51 and rest on the ends of spaced rows of bolts 57 and 58 threaded into the channel iron 39 and into bosses 59 on the bottom 7, respectively. These cams and bolts serve to support the connection so that the full weight of the plates 49, 51, and 53 need not be supported by

the flexible members 52, and 54, the cams moving over the bolts as the chamber is raised or lowered.

Stock is supplied to the interior of the chamber from a distributor pipe 61 by any of numerous and well known flexible connections. In this particular instance, I have shown a nipple 62 threaded into a flange 63 on each of the troughs 11 and 12. An elbow 64 is threaded onto the nipple 62 and serves to receive a short piece of pipe 65, the opposite end of which is received in a second elbow 66. A second short piece of pipe 67 extends between the elbow 66 and an elbow 68 which in turn is connected to a T 69 on the pipe 61 by means of a pipe 71. It will be seen that if these pipes and elbows are not screwed together too tightly they will permit sufficient movement in the joints, for 20 the raising and lowering of the movable portion of the chamber.

A shaft designated generally by the numeral 72 is supported near its ends in bearings 73 and 74 which are in turn supported upon cross-arms 75 and 76 supported upon and secured to the vertically adjustable portion of the chamber by means of bolts 77. One end of the shaft 72 extends outward over the trough 11 and is supported in a bearing 78 on the trough, the extreme end of the shaft carrying a sprocket 79 over which is trained a chain 81 which serves to drive the shaft. Sleeves such as shown at 82 are positioned on an eccentric portion 80 of the shaft 72 adjacent to the bearings 73 and 74, the sleeves being fixedly secured thereto by means of set screws 83. The sleeve 82 is of variable wall thickness such that it may be adjusted to offset the eccentricity 40 of the shaft portion 80 or to add to this eccentricity as desired. Bearings 84 are positioned on the sleeves 82 and are fixedly secured to the ends of a cylinder 85 by means of cap screws 86. The cylinder 85 carries 45 a plurality of webs 87, 88 and 89 shown best in Fig. 3, which extend radially from the lower side of the cylinder 85, each of the webs consisting of longitudinally spaced arms such as shown at 91 and 92 in Fig. 4. An arcuate pulsating element 93 having a plurality of small openings 94 is fixedly secured to the webs 87, 88 and 89 by means of cap screws 95, whereby the pulsating element 50 may be eccentrically supported with respect to the cylinder 85 depending upon the position of the sleeves 82. This pulsating element extends the full length of the cylinder 85 and is arcuately curved transversely of its length through a portion of a circle, as best 60 shown in Fig. 3. To prevent rotation of the pulsating element an upwardly extending arm 96 is fixed to the cylinder 85 and is provided at its upper end with a pin 97 rotatably secured in a block 98 which is in turn 65 slidably positioned in arcuate arms 99 and

101 secured to the chamber by means of cap screws 102 at each end thereof. This construction permits the arm 96 to move vertically with respect to the arms 99 and 101 and to have rotative movement with respect thereto, thus providing a guide for controlling the movement of the pulsating element 93.

A flow evening and screening cylinder designated generally by the numeral 103 is concentrically positioned with respect to the pulsating element 93 and rests between said element and the bottom 7 of the movable portion of the chamber. This consists of a surface covering 104 and a frame having spaced longitudinal bars 105, spaced circumferential bars 106 and channeled end members designated generally by the numeral 107. The covering 104 is secured to the frame by means of screws 110 and strips 108 secured to the longitudinal frame members 105 through cap screws 109. The covering 104 is provided with a plurality of longitudinally and circumferentially spaced slots 111, the slots being of substantially greater length than width for the purpose of passing the stock through the flow evening and screening cylinder. A more definite idea of the shape characteristics of these slots may be had by a comparison of Figs. 3 and 4. The diameter 95 of the cylinder is such that it will project a substantial distance above the open upper side of the chamber when in operative position with respect to the bottom 7 thereof, as shown in Fig. 3, so that driving and cleaning mechanisms presently to be more fully described, may be positioned above the chamber. It will be seen that upon rotation of the shaft 72 the sleeve 82 will be rotated causing the pulsating element 93 to be oscillated in a manner to cause the stock between the pulsating element and the screening cylinder to be forced through the screening openings 111 to the outside of the cylinder. Furthermore, the manner of oscillation is such as to utilize the entire area of the screening cylinder which may be at the time submerged in the pulp and that no quiescent zones are produced along the surface thereof. 110

The screening cylinder is supported for rotation in the trough members 11 and 12 in a manner best shown in Fig. 4. This means consists of right angled grooves positioned on the inner surface of the trough members 11 and 12 adapted to receive the members 107. An arcuate rubber bearing member 112 is positioned along one side of the groove opposite the end 113 of the member 107, and a rubber bearing member 114 is positioned along the circumferential face of the groove opposite the bearing surface 115 of the members 107, the width of the bearing member 114 being such as to leave a space 116 between the edge thereof and the face of the bearing member 112. The end member 117

107 is provided with a channel 117 extending therein circumferentially of the screening cylinder and with a plurality of circumferentially spaced openings 118 and 119 extending from the channel 117 to the end 113 thereof and to the circumferential bearing face 115 thereof. The channel 117 and the openings 118 and 119 serve to conduct lubricating liquid to the interfaces between the end member 107 and the rubber bearing members 112 and 114. This lubricating fluid usually consists of water and means are provided for maintaining a substantially constant level of water in the channel 117, this means being shown in Fig. 5, and consisting of a supply pipe 121 supported on each of the arms 99 and 101, presently to be more fully described. The nozzle 122 is positioned to deliver a stream of water against the outside of the end member 107 in the vertical plane of the openings 119 so that as the cylinder revolves, water will be sprayed through the openings into the channel 117. In this way water is constantly supplied to the channel 117 and is maintained at substantially the level of the upper edge of the trough members 11 and 12. An opening 123 in the trough members 11 and 12 connects the space 116 with the atmosphere and permits the escape of water draining from the bearing surfaces.

Means are provided for keeping the inside of the screening cylinder 103 free from pulp and slime and for conducting away the solids which fail to pass through the openings therein. This consists of a spray pipe 124 which may advantageously be supported in cradles 125 on the arms 99 and 101 as shown in Fig. 4. A suitable connection 126 is provided for supplying water to the pipe 124. The pipe 124 is arranged to provide a spray of water against the outside of the cylinder 103, the water passing through the openings 111 thereof. A tray or pan 127 is fixedly supported on the top side of the cylinder 85 in a position to receive the water from the spray and the solid particles removed from the screening cylinder by action of the spray. Pipes 128 serve to drain the tray 127. In order to confine the splash caused by the impingement of the spray water against the outside of the screening cylinder 103, angle iron members 129 and 131, carrying flexible members 132 and 133 in close proximity to the outer surface of the cylinder, are secured at opposite ends to the arms 99 and 101, extending therebetween and being affixed thereto by means of bolts 134.

The shaft 72 and the screening cylinder 103 are driven from a motor 135 or other prime mover supported upon channel iron members 136 which rest upon bracket members 137 secured to the side of the movable portion of the chamber. One end of the motor shaft 138 is provided with a sprocket 139 for receiving the chain 81 through which the

shaft 72 is driven. The opposite end of the motor shaft 138 is connected to a gear box 141 through which a shaft 142 is driven, the free end of the shaft having bearing support in a bearing 143. A chain 144 is driven from the shaft 142 by means of a sprocket and is trained over a sprocket on a gear shaft 145 rotatably supported in the arm 101. A gear 146 on the shaft 145 meshes with a large ring gear 147 positioned on the periphery of the flow evening and screening cylinder 103 whereby rotation of the shaft 142 brings about rotation of the cylinder 103.

Stock is supplied to the troughs 11 and 12 from the main supply pipe 61 and from the troughs enters the interior of the pulsating element 93 from opposite ends thereof and will fill the chamber to a predetermined level. Oscillation of the pulsating element causes the stock to move through the small openings in the screening cylinder, the oscillation bringing about dispersions of the fibers in the stock and uniform distribution thereof. It will be seen that a further action of the pulsating element is to tend to bring about a movement of the stock in the direction of movement of the web forming element. As soon as the stock passes through the pulsating element it is brought in contact almost immediately with the rotating screening cylinder 103 and here again it must pass through a plurality of small openings. The constant rotation of the cylinder 103 not only assists in the preparation of the stock but imparts thereto a direction of flow substantially parallel with the movement of the web forming element. As the stock leaves the cylinder 103 it is conducted almost immediately through the slices 28 and 29 onto the web forming element, so that no time nor opportunity is allowed for the fibers to settle out or felt. In other words, the stock coming from the screening cylinder is in the best condition possible for application to the web forming element and, in this condition, the stock is directly applied to the web forming element.

Attention is called to the fact that the oscillation or shaking effect of the pulsating element is radial and that the action is uniform throughout the surface of the screening cylinder in contact with the stock whereby all of the screening area is utilized to its greatest efficiency. This results in substantially greater uniformity of action, in that it leaves no dead spots or quiescent zones along the surface of the screening cylinder which may offer an opportunity for segregation of the fibers. Furthermore, this action also materially assists in bringing about the reversal of the direction of flow and in evening out the flow characteristics of the stock, thereby simplifying and supplementing the normal action of the flow evening and screening cylinder.

Mechanism has been shown and described for altering the elevation of the vertically movable portion of the chamber and of the pulsating element and screening cylinder.

5 As a result of this construction it is possible to regulate the preparation of the stock independently of the head. In other words, in the old type of mechanism it was necessary to set the head for the maximum capacity 10 without regard to the character, consistency, or amount of the stock. With the present construction the operator may regulate the head to correspond with the speed of the machine and independently regulate the pulsating element and screening cylinder to give 15 the best preparation of the stock by varying the height of the movable portion of the chamber, thereby varying the amount of screening cylinder used. The operator may 20 also vary the speed of the oscillation and vary the length of the oscillation stroke. Thus, this construction permits of materially greater 25 flexibility in operation whereby the stock is placed on the web forming element in substantially better condition than has heretofore been possible.

It will furthermore be seen that through my improved construction I have completely eliminated the customary head box, together 30 with the objectionable features thereof and, instead, pass the stock from the screening cylinder directly onto the web forming element, leaving no opportunity for the fibers to felt or mat while the flow of the stock 35 is being evened out. The stock is continuously in movement thereby largely eliminating the possibility of slime collecting. However, should a small amount of slime appear 40 it is immediately removed by the rotating screen cylinder.

Attention is directed to the fact that the present device may be used with a battery of screens to receive the stock therefrom and deliver it to the web forming element.

45 While I have thus described and illustrated a specific embodiment of my invention I am aware that numerous alterations and changes may be made therein without materially departing from the spirit of the invention and 50 the scope of the appended claims in which—

I claim:

1. In a paper making machine, the combination with a web forming element, of a chamber positioned to supply stock directly 55 to said web forming element, and means in said chamber for screening and evening the flow of said stock.

2. In a paper making machine, the combination with a web forming element, of a chamber positioned to supply stock directly 60 to said web forming element, a screen in said chamber for screening said stock and imparting desired flow characteristics to said stock for application to the web forming element, and means for imparting a pulsating

movement to the stock to force it through said screen.

3. In a paper making machine, the combination with a web forming element, of screening mechanism for said stock, means in said 70 screening mechanism for imparting desired flow characteristics to the stock, and means for conducting the emerging stock directly onto said web forming element.

4. In a paper making machine, the combination with a web forming element, of a chamber, substantially concentric pulsating and screening elements positioned in said chamber, and means for passing the stock first through the pulsating element then 80 through the screening element and thence directly onto said web forming element.

5. In a paper making machine, the combination with a web forming element, of a chamber for receiving the stock, an arcuate 85 pulsating element positioned in said chamber, a screening cylinder surrounding said pulsating element, means for shaking said pulsating element to pass the stock through the screening cylinder, and means for rotating the cylinder to even the flow of the stock 90 passing to said web forming element.

6. In a paper making machine, the combination with a web forming element, of a chamber for receiving the stock, an arcuate 95 pulsating element positioned in said chamber, a screening cylinder surrounding said pulsating element, means for shaking said pulsating element to pass the stock through the screening cylinder, means for rotating 100 the cylinder to even the flow of stock passing to said web forming element, and means for adjusting the height of said chamber to regulate the submergence of the elements therein.

7. In a paper making machine, the combination with a web forming element, of a chamber, slices arranged to control the flow of stock from said chamber to said web forming element, screening and flow evening elements in said chamber, and means for raising and lowering said chamber to regulate the amount of submergence of said elements in the stock.

8. In a paper making machine, the combination with a web forming element, of a chamber, slices arranged to control the flow of stock from said chamber to said web forming element, pulsating and screening elements in said chamber, means for shaking 110 said pulsating element, means for rotating said screening element, and means for raising and lowering said chamber to regulate the amount of submergence of said elements in the stock.

9. In a device of the character described having screening and flow evening elements, a chamber having a slice gate portion of fixed elevation, a portion of variable elevation, and an extensible, flexible connection between said 120

portions forming a substantial liquid-tight junction therebetween at all elevations of said last mentioned portion.

10. In a device of the character described having screening and flow evening elements, a chamber having a slice gate portion of fixed elevation, a portion of variable elevation, an extensible, flexible connection between said portions forming a substantially liquid-tight junction therebetween at all elevations of said last mentioned portion, and means for supporting said connection in the various elevations of the portion of variable elevation.
15. 11. In a device of the character described having screening and flow evening elements, a chamber having a slice portion of fixed elevation, a portion of variable elevation, and a flexible, extensible connection therebetween comprising a pair of parallelly spaced plates flexibly connected to one of said portions, forming the groove of a tongue and groove connection, and a plate flexibly connected to the other of said portions, forming the tongue of said connection and being adapted to move between said parallel plates to lengthen or shorten said connection.
12. In a device of the character described, the combination of a chamber, an arcuate pulsating element supported in said chamber for oscillatory motion, a screening cylinder surrounding said pulsating element supported to rotate on a fixed center, means for supplying paper stock to the center of said cylinder, and means for conducting the stock from the outside of said cylinder directly to a web forming element.
13. In a device of the character described, the combination of a chamber, a pulsating element supported in said chamber, crank means for supporting said pulsating element and imparting oscillatory motion thereto, a perforate cylinder surrounding said pulsating element supported to rotate on a fixed center, means for supplying stock to the center of said cylinder from opposite ends thereof, and means for conducting stock from the outside of said cylinder.
14. In a device of the character described, the combination of a chamber, a pulsating element supported in said chamber, means for supporting said pulsating element for oscillatory motion including a crank and a guide, means for rotating said crank, a perforate cylinder surrounding said pulsating element supported to rotate on a fixed center, means for rotating said cylinder including a gear on the periphery thereof and a driving

gear to engage the same, means for supplying stock to the center of said cylinder, and means for conducting stock from the outside of said cylinder.

15. In a device of the character described, a rotating cylinder having bearing surface on the periphery thereof at each end, rubber bearing surfaces held thereagainst in supporting relation, and means for conducting a liquid to the bearing interface at frequent intervals along said bearing surface.

16. In a device of the character described, a chamber having end walls, arcuate rubber bearing faces in said end walls, a perforate cylinder having peripheral bearing surfaces shaped to support said cylinder on said bearing faces for rotation, and means for conducting a lubricating liquid through said bearing surfaces at frequent intervals along said surfaces.

17. In a device of the character described, a chamber having end walls, arcuate rubber bearing faces in said end walls, a perforate cylinder having circumferential channels at each end, peripheral bearing surfaces shaped to support said cylinder for rotation on said bearing faces and openings from said channel through said bearing surfaces to conduct a lubricating liquid thereto, and means for supplying a lubricating liquid to said channels.

18. In a device of the character described, a chamber having end walls, arcuate rubber bearing faces in said end walls, a perforate cylinder having circumferential channels at each end, peripheral bearing surfaces shaped to support said cylinder for rotation on said bearing faces and openings from said channel through said bearing surfaces to conduct a lubricating liquid thereto, means for supplying a lubricating liquid to said channels, and means for conducting away the liquid passing through the bearings.

19. In a paper making machine of the character described, a rotating screening cylinder, a chamber surrounding said cylinder, a pulsating element of substantially the same curvatures said screening cylinder located in concentrically spaced relation thereto having a plurality of openings, eccentric means for supporting said pulsating element arranged to be rotated to impart a rotating pulsation to the stock between said cylinder and said pulsating element, and means for conducting incoming stock to the interior of said pulsating element.

EARL E. BERRY.
